(57) **CLAIM**

The ornamental design for pet glasses, as shown and described.

DESCRIPTION

FIG. 1 is a front, right and perspective view of pet glasses, showing my design.

FIG. 2 is a rear, right and perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines depict portions of the pet glasses that form no part of the claimed design. The lines on the lens indicate the transparent state of the lens.
